WAVE SIGNAL RECEIVING SYSTEM

Harold A. Wheeler, Great Neck, N. Y., assignor
to Hazeltine Corporation, a corporation of
Delaware

Application February 27, 1935, Serial No. 8,467

16 Claims. (Cl. 250—20)

This invention relates to signal-modulated carrier wave signaling systems, and more particularly to such systems designed for distortionless and selective reception of radio signals, free from interfering signals and other disturbances.

In my copending application, Serial No. 691,927, filed October 3, 1933, of which the present application is a continuation-in-part, there is described a system for receiving signal-modulating carrier waves and utilizing only the carrier and either sideband of modulation. As explained at length in that application, such a system has a number of advantages, among which may be noted that the signal selecting circuits need be designed to pass only one-half the band of frequencies required by a conventional receiver, resulting in increased selectivity and a minimum of interference. Further, the system may be adjusted to receive that sideband which is subject to a minimum interference from signals on adjacent channels.

The system of my aforesaid application included as desirable features thereof, provision for adjusting the circuits so that the signal carrier is located at either one edge or the other of the narrow frequency band passed by the selecting circuits; an arrangement of "selective admission" effective to increase the response of a receiver when it is properly tuned to receive a single sideband; an automatic volume control of the suspended type, that is, one which operates to reduce the amplification of the system only for received signals above a predetermined intensity; a reverse automatic volume control associated with the main volume control, procuring the required ultimate variation of the bias voltage for a gain control of the system without any appreciable change in the amplified carrier output; and a quieting system effective to maintain the system unresponsive unless the received signal exceeds a predetermined intensity and unless the receiver is correctly tuned.

My present invention relates to signal translating, amplifying and controlling circuits and systems which, while of general application, are particularly suitable for use in connection with signal-modulated carrier wave systems of the type disclosed and claimed in my aforesaid copending application and briefly described above. Included in my present invention is an arrangement for optionally operating a single sideband type of receiving system for double sideband reception, which may be found desirable when a very weak signal is being received and a condition of very high selectivity must be provided,

The above and other features of the invention will become apparent from the following detailed description and reference to the accompanying drawings.

In the accompanying drawings, Fig. 1 is a diagram showing in generalized form a receiving system of the superheterodyne type, adapted for single sideband operation in accordance with this invention; Fig. 2 is a schematic circuit diagram of a receiver constructed in accordance with the general diagram of Fig. 1; Fig. 3 shows graphically the selectivity of the intermediate-frequency amplifier of Fig. 2; Fig. 4 shows graphically the fidelity of the audio amplifier of Fig. 2 and illustrates the compensation for the loss of part of a sideband under the condition of single sideband reception; Fig. 5 shows the change of audio-frequency fidelity upon change of volume level; Fig. 6a illustrates the responsiveness of the intermediate-frequency trap of Fig. 2; Fig. 6b illustrates the relationship between grid bias and plate current of the "quieting" tube; Fig. 6c illustrates the amplification characteristic of the quieting system; Figs. 6d and 6e illustrate, respectively, the variations in plate current and in relative amplification of the quieting system; and Fig. 7 shows the change of automatic volume control bias voltage with change of intermediate-frequency carrier voltage, in the receiver of Fig. 2.

The general principles of single sideband reception and their application to a superheterodyne radio receiver are discussed at length in my aforesaid copending application, to which reference is made. In brief, the signal-selecting circuits for transmitting the signal-modulated carrier frequency are designed and adjusted to pass only the carrier, one sideband, and the inner part of the other sideband, so as to include the complete audio-frequency spectrum with each audio-frequency component represented in its proper relative magnitude. In case of a receiver having a tuned radio-frequency amplifier, but not the superheterodyne feature, the general principles of operation are otherwise the same as in a conventional double sideband receiver, provision being made for compensating for the loss of signal intensity by selecting against the outer part of the other sideband. It is there explained, also, that in the case of superheterodyne radio receivers, to which the present invention is illustrated as applied, one sideband of the signal-modulated carrier frequency, when modulated in a frequency-changing circuit by the locally generated oscillations, whose frequency is greater

than the received carrier frequency, results in a single sideband of difference frequency or intermediate frequency shifted along the frequency scale but having characteristics in all other respects the same as the original sideband, save only that the high and low sidebands are reversed in position on the frequency scale. The amplification and detection of the intermediate-frequency modulated carrier through the remaining portions of the receiving system are accomplished in the same general manner as in a conventional receiver. However, certain features described briefly above may be utilized to advantage in a single sideband system of my invention to improve the selectivity, sensitivity and fidelity of reproduction of the system.

Circuit arrangement and general operation

Fig. 1 is a generalized circuit diagram illustrating the arrangement of a superheterodyne receiver adapted for single sideband operation in accordance with this invention. The path traversed by signals between the antenna and the loudspeaker is shown conventionally. There are provided an antenna 30 and ground 31 for intercepting the signals, which are then supplied, in order, to a radio-frequency amplifier 32; a local oscillator and modulator 33; an intermediate-frequency amplifier 34; a diode rectifier 35; an audio-frequency "quieting" amplifier 36; an audio-frequency amplifier 37; and a loudspeaker 38.

With reference to this main signal path, the radio-frequency signal is received in the usual manner by the antenna 30 and selected and amplified at the signal frequency in the radio-frequency amplifier 32, which for broadcast reception is capable of tuning over the frequency range of about 550 to 1500 kilocycles. The oscillator and modulator system 33 converts the radio-carrier frequency signal to an intermediate-carrier frequency signal in the manner well understood in the art. The intermediate-carrier frequency will be one of two frequencies depending upon which of the two sidebands is being selected. These two alternative intermediate-carrier frequencies will, therefore, differ by the width of a sideband, which may be in the neighborhood of 3 kilocycles. These intermediate-carrier frequencies may conveniently be taken as 173.5 or 176.5 kilocycles, depending upon which sideband is to be utilized. The signal is further amplified in the intermediate-carrier frequency amplifier wherein the carrier and one sideband are selected, the band width passed by this amplifier being, for the particular intermediate-carrier frequencies mentioned above, 173.5 to 176.5 kilocycles, centered at 175 kilocycles. The diode rectifier 35 derives from the carrier and the single intermediate-frequency sideband the audio frequencies of modulation, which are then amplified by the audio amplifiers 36 and 37, from whence they are supplied to the loudspeaker 38.

For the purpose of maintaining the volume output of the receiver substantially constant in spite of wide variations of received signal intensities, there is provided an automatic volume control system comprising connections 40 from the output terminals of intermediate-frequency amplifier 34 to the following elements connected in succession: an intermediate-frequency trap 41, an intermediate-frequency amplifier 42, a diode rectifier 43 and a diode "suspender" 44. The functions of the intermediate-frequency trap 41 and of the diode suspender 44 are described below. In accordance with the operation of the automatic volume control system, there is created

at the diode suspender 44 a unidirectional voltage which varies with the received signal intensity; and this unidirectional voltage is applied through the automatic volume control bias connection 45 to the control elements of amplifiers 32 and 34 and oscillator-modulator 33.

For the purpose of insuring the proper variation of control bias voltage over a wide range of received signal intensities there is provided a connection 46 from the intermediate-frequency 10 amplifier 34 of the main signal path to a control element of the intermediate-frequency amplifier 42 in the automatic volume control system. This is a "reverse control bias" connection, the function and operation of which are more fully de- 15 scribed below.

In accordance with a feature of the invention, there is created what is here termed "selective admission", which is an operating characteristic whereby the user is constrained to tune the receiver so that the intermediate-carrier frequency is located at either edge of the selected intermediate-frequency band, that is, 173.5 or 176.5 kilocycles, in this case. The feature of selective admission is effected by the action of the intermediate-frequency trap 41 of the automatic volume control system, and is perfected by the co-operation of the quieting system associated with amplifier 36, as will more fully appear below. The trap 41 contains a selective circuit proportioned to cause the automatic volume control bias of conductor 45 to become partially relaxed when the receiver is so tuned that the intermediate-carrier frequency is located exactly at the center of the selected intermediate-frequency band, that is, 175 kilocycles in this case. At this tuning point, the intermediate-frequency carrier voltage present at connections 40 is maintained at a substantially higher level than in the case of any other tuning points.

There is associated with the audio-frequency amplifier 36 a quieting system whereby sideband selection and quieting between stations are obtained by the manner in which the amplifier is operated. To secure this operation, the amplifier 45 tube is so adjusted that its gain is a maximum at a critical negative value of grid bias, and rapidly approaches zero for greater or lesser biasing voltages.

The biasing voltage for the quieting tube is obtained from the diode rectifier 35 and is proportional to the carrier voltage at connections 40. When no signal is present, or when the average rectified signal or noise voltage is less than the critical bias, the gain through the quieting amplifier 36 is substantially zero, and there is practically no transmission through this amplifier. Also, when a strong intermediate-frequency carrier signal is tuned to the center of the band (175 kilocycles in this case), the bias developed by the rectifier 35 becomes considerably greater than the critical value, and the gain of amplifier 36 is again reduced nearly to zero. The critical bias, which produces this operative condition, is obtained only when the intermediate-frequency 65 carrier is detuned to either edge of the selected band (173.5 or 176.5 kilocycles in this case). It should be noted that the grid bias is determined by the amplitude of carrier voltage at connections 40. This amplitude is in turn determined by the 70 response characteristic of the intermediate-frequency discriminating circuit, or trap 41, in co-operation with the automatic volume control system. The trap should, therefore, be made to have such a characteristic that the critical bias 75

is obtained at either edge of the intermediate-frequency band.

Fig. 2 is a detailed circuit diagram illustrating a superheterodyne receiver adapted for single sideband operation, designed according to the general arrangement of Fig. 1. The rectangular boxes of Fig. 1 are indicated in Fig. 2 in dotted lines and are similarly numbered.

In Fig. 2, the radio-frequency amplifier 32 comprises a pentode tube 51 suitably coupled to the antenna 30, and has associated therewith three simultaneously tunable selecting circuits, two of which, designated 130 and 131, are located ahead of the amplifier, and the other of which, 132, is coupled between the amplifier and the tube 52. These circuits are tuned by variable condensers 135, 136 and 137, respectively.

The oscillator and modulator arrangement 33 comprises the hexode oscillator-modulator tube 52. Such an oscillator-modulator circuit constitutes no part of this invention and consequently is not described in detail here. This type of oscillator-modulator is described in my Patent No. 1,958,027, issued May 8, 1934. This oscillator-modulator comprises a frequency-determining circuit 99 having a variable tuning condenser 215.

The tuning condensers 135, 136, 137 and 215 are ganged together by a mechanical unicontrol device indicated by the dashed lines U. These condensers constitute the tuning means for tuning the signals to the desired intermediate-frequency band.

The output of the oscillator-modulator is coupled to the input of the intermediate-frequency amplifier 34 which comprises two amplifying tubes 53 and 54 and the three intermediate-frequency coupling systems 160, 161 and 162 located before, between, and after, the amplifying tubes.

The signals are rectified in the diode portion of a double-diode pentode tube 55' in stage 35. Only one of the diodes is employed for signal detection, this particular diode comprising the cathode 163 and one of the diode anodes 164. The pentode elements of this tube are used in the audio-frequency quieting amplifier 36. For the purpose of illustration, therefore, tube 55' is shown again in the audio amplifier section 36, where it is designated as tube 55. This second illustration of the same physical elements is proper and convenient because, insofar as circuit operation is concerned, the action is that of two separate and distinct tubes.

The rectified current flows through a resistor 83, from whence rectified voltage is impressed upon the control grid of the pentode amplifier 55 by way of conductor 166 through resistors 84, 87 and 90 and condensers 86, 89 and 88. The resistor 87 and the condenser 89 are proportioned to provide proper audio-frequency compensation, as will be more fully described hereinafter.

The anode of pentode amplifier 55 is coupled to the second audio-frequency amplifier tube 56 through a system of condensers and resistances including the voltage divider 180 from which any desired proportion of the audio-frequency voltage at the output of tube 55 may be applied to the input of tube 56. The audio signals are further amplified in the push-pull amplifier including tubes 57 and 165, whence they are conveyed to the loudspeaker 38.

It is of primary importance that the receiving system select a band of frequencies having a width about equal to the highest required audio frequency of modulation. Since the selective circuits of the audio-frequency amplifier 32 cannot

be tuned as accurately as those of the intermediate-frequency amplifier 34, it is preferable that they be tuned sufficiently broadly to pass a band of this width with a uniformity within one decibel. The necessary selection is, therefore, procured mainly by the permanently tuned coupling systems of the intermediate-frequency amplifier 34. This amplifier includes a coupling system 160 comprising two double-tuned transformers 167 and 168, each preferably designed to have nearly optimum coupling, and a coupling system 161 comprising a double-tuned transformer preferably having a uniform transmission characteristic over a band of frequencies corresponding in width to one sideband.

The selectivity characteristics of a typical receiving system of the type described, designed to pass an intermediate-frequency band of 173.5 to 176.5 kilocycles, are shown in Fig. 3. In this figure the intermediate-frequency spectrum of a signal is represented at 26, being centered at frequency f_{ic} of 173.5 kilocycles and having upper and lower intermediate-frequency sidebands with boundaries f_{lb} , f_{ub} , respectively (corresponding to the lower and upper carrier sidebands, respectively). In this same figure the curve 110 represents the selection characteristics of the intermediate-frequency selecting circuits of amplifier 34 centered at a frequency f_{ic} of 175 kilocycles and flat within one decibel over a band of three kilocycles; that is, over the upper intermediate-frequency sideband. There is also shown in this figure the intermediate-frequency spectrum of two other signals 111 and 112, corresponding to adjacent broadcast channels, and centered at $f_{ic}-10$ and $f_{ic}+10$ kilocycles, respectively; that is, separated by 10 kilocycles from the signal 26 being received.

For the purpose of this example, it is assumed that signal 111 is stronger than signal 112; hence, the receiver is shown to be properly tuned to the sideband which is farthest away from the stronger signal. The intermediate-carrier frequency of signal 111, and also its sideband nearest to signal 26, are subject to 16 decibels more attenuation than the carrier frequency and nearest sideband of the signal 112. Both of the adjacent channel signals are attenuated much more than they would be if the curve 110 were doubled in width to include both sidebands; and it is shown how the receiver may be tuned to discriminate against the stronger of the signals in the two adjacent channels.

Two of the most important problems encountered in the use of this receiver for single sideband reception are: (1) to cause the operator to tune the receiver correctly so that the intermediate-carrier frequency is located at one edge of the selected frequency band, as shown in Fig. 3; and (2) to compensate for the loss of nearly all of the rejected sideband.

The first of these problems is solved by a system of "selective admission", which greatly lessens or entirely quiets the response of the receiver when not correctly tuned. This system, which has been mentioned above and is described below in more detail, is made necessary or at least desirable because the sound at the loudspeaker is harsh and unpleasant when the carrier frequency is tuned too far off of the edge of the transmitted sideband.

The second of these problems is solved by the use of resistor 87 and condenser 89 associated with the audio-frequency tube 55. In Fig. 4, which is plotted as relative gain or responsiveness against

audio frequency, curve 113 indicates the equivalent audio-frequency loss resulting from the cutting out of most of one sideband. This loss is shown to be about 3 decibels at 1 kilocycle and 6 5 decibels at 3 kilocycles, in the case of the particular receiver under discussion. Accordingly, the elements 87 and 89 are proportioned to produce a relative audio-frequency gain which varies substantially as represented by curve 114. This latter 10 variation being complementary to that of curve 113, uniform overall audio-frequency response is produced as represented by curve 115. In producing this compensation it has been found proper 15 to make the impedances of elements 87 and 89 of the same order of magnitude at one kilocycle.

Automatic volume control

The proper operation of the quieting system requires that the output of the intermediate-frequency amplifier 34 be maintained at a constant predetermined value, substantially independent of both the received signal intensity and the percentage of modulation. The arrangement and operation of the automatic volume 20 control system is described with reference to Figs. 1, 2 and 7. Intermediate-frequency voltage is derived from a coil 71 tuned by a condenser 72 and coupled to the primary coil of the intermediate-frequency coupling system 162, 25 and, by means of connection 40', coupling transformers 74 and 67 of the intermediate-frequency trap 41, and intermediate-frequency amplifier tube 58, it is applied between the cathode 61 and diode anodes 60 and 172, constituting the 30 rectifying portion of a double diode pentode tube 59, hereinafter called the A. V. C. diode since it determines the operation of the automatic volume control.

Associated with the diode rectifier in the tube 40 59 is a voltage divider comprising resistors 62 and 63 serially connected across a battery 66 through the diode 55'', constituting cathode 168 and diode anode 175 of the multi-purpose tube 55 referred to above, which is referred to here- 45 in as the suspended diode. The anodes 60 and 172 are connected to the junction 64 of resistors 62 and 63 which are so proportioned that, in the absence of a signal, the anodes are maintained substantially at the same voltage with respect 50 to ground as the cathode 61, which is biased with respect to ground due to the flow of the space current of the pentode portion of the tube 59 through the resistor 65. The result is that there is substantially no flow of current in the 55 diode section of the tube 59, but it is in an incipient conductive condition and carries current upon the supply of intermediate-frequency voltage to the anodes 60 and 172. Under these conditions points 39 and 107, which are connected to the grid of the pentode 59 and to the anode 175 of the diode 55'', respectively, are effectively grounded through the diode 55'' so that no automatic volume control bias voltage is supplied to the conductor 45.

Upon the reception of a signal, however, an intermediate-frequency voltage is impressed on the diode of the tube 59 and rectified current flows through resistors 62 and 63 in parallel, decreasing the current and voltage drop in 63. 60 When the intermediate-frequency voltage exceeds a value corresponding to a predetermined signal intensity, the point 64 becomes negative with respect to ground. Under these conditions the diode 55'' is ineffective, so that the points 75 39 and 107 become equally negative as the point

64. A further increase in signal intensity increases the negative voltage at these points, which is applied through the conductors 45 and 45' to the control grids of the intermediate-frequency amplifying tubes 53 and 54, the radio-frequency amplifier tube 51, and the oscillator-modulator tube 52, respectively. 5

The control grid 173 of the tube 59 is also effective under these conditions to reduce the space current in this tube, and thus to reduce 10 the voltage across the resistor 65. In this manner, the change of negative voltage on the cathode 61, relative to ground, augments that of the anodes 60 and 172, with respect to the cathode 61, thereby increasing the resultant negative 15 voltage existing at the point 64, and therefore at the points 39 and 107.

The operating characteristics of a typical automatic volume control circuit operating on these principles are shown in Fig. 7 of the drawings, in which the line 123 represents the voltage of point 64 with respect to ground, which voltage changes negatively in proportion to the signal intensity. In this figure the dimension 124 indicates the voltage across resistor 62 and 20 the dimension 125 that across resistor 63. When the signal intensity increases to the point where the voltage of the junction point 64 becomes negative, the current in the diode 55'' is reduced to zero and the average voltage applied to the 25 automatic volume control bias conductors 45 and 45' from the points 39 and 107 becomes equal to that at the point 64.

As stated above, a decrease in the voltage of the points 39 and 107 decreases, by virtue of the 30 connection of the grid 173 thereto, the space current in the tube 59, and thus effectively increases the change of negative voltage of the diode anodes 60 and 172, to effect a resultant 35 increase in the negative voltage of the point 64. 40 This is represented by the increased slope of the curve 123 at its intersection with the zero axis. If the effect of the pentode 59 were omitted, the curve 123 would continue at its original slope, as shown by the dotted line 121. 45 In this diagram the ordinate 126 represents the voltage of the point 107 relative to ground.

The action of such automatic volume control biasing connections for controlling the gain of amplifiers and modulators is well understood in 50 the art and requires no detailed discussion here. It is sufficient to state that the connections 45 and 45' cause the control grids of the controlled tubes to become more negative when the signal strength increases above a predetermined value, 55 thereby maintaining the intermediate-frequency output level fairly uniform.

The desired highly uniform output of intermediate-frequency amplifier 34 is accomplished by means of a "reverse automatic volume control" bias voltage provided by a connection 46 60 extending from the cathode of amplifier tube 54 to the cathode of amplifier tube 58 of the automatic volume control system. This common cathode connection 46 is connected to ground 65 through a resistor 68 which carries the space current of both tubes; hence, the space current of tube 54 partially controls the grid-cathode bias of tube 58 and, therefore, the gain of this latter tube. This bias on tube 58, however, varies oppositely 70 from that on the controlled amplifier and modulator tubes of the main signal path. When the grid-cathode bias of tube 54 becomes greater by automatic volume control action, its amplification and space current decrease, and consequent- 75

ly the grid-cathode bias of tube 58 decreases, causing the gain of the latter tube to increase somewhat. Therefore, the increased intermediate-frequency voltage, which is required by the A. V. C. diode in tube 59 to decrease the amplification of amplifier 34, is supplied by the increased gain of tube 58 and without any increase of the input to the latter tube, or of the output of amplifier 34. This action is called reverse automatic volume control because the gain of tube 58 is automatically varied oppositely to that of tubes 51, 52, 53 and 54. Quantitatively, the gain of tube 58 can be just about doubled by this reverse automatic volume control connection, this being sufficient to vary the intermediate-frequency voltage on the A. V. C. diode of tube 59 over the desired wide range without any appreciable variation of the intermediate-frequency input to tube 58.

The "reverse" and the "suspended" automatic volume control actions cooperate to maintain the output of intermediate-frequency amplifier 36 very nearly uniform during reception of large variations of signal intensity.

25 Selective admission

The "selective admission", mentioned above, is provided to cause the oscillator correctly to tune the receiver for single sideband reception. This includes means for causing the audio-frequency output to reach sharply a maximum value when the intermediate-carrier frequency is tuned on either edge of the band selected in the intermediate-frequency amplifier 34. This action results from a cooperation between the frequency discriminating trap 41 and the rest of the automatic volume control channel and the quieting system associated with amplifier 36.

The trap circuit contains a shunt arm to ground comprising an inductance 69 and a condenser 70, these two reactive elements being tuned very sharply to the center of the intermediate-frequency band (175 kilocycles in this case), so that this center frequency is sharply attenuated. Condenser 70 is adjustable to enable the trap to be readily tuned to the center frequency. Coil 71 is smaller than the primary coil of coupling system 162 so as to produce a voltage step-down from the output of tube 54 to the trap circuit. Transformer 74, which couples the trap to the input of tube 58 is a step-up transformer in which the secondary coil 78 is larger than the primary coil 49. A condenser 75 is inserted in series with the primary coil 48 of transformer 74 and serves to tune the said primary coil broadly to the center of the selected band (175 kilocycles). The resistor 77 has the proper value to broaden the resonance of elements 49 and 75; and the resistor 76 serves to limit the current which enters the trap from coil 71. The ratios of the transformers at the input and output of the trap are chosen to permit coil 69 to be of the same order of magnitude as the secondary coil 78 of transformer 74, in spite of the fact that transformers 73 and 74 work out of, and into, respectively, circuits of high impedance.

The effect of the automatic volume control system including intermediate-frequency trap 41 upon the rectified output of the signal rectifier at tube 55 is shown in Fig. 6a in which curve 118 represents the rectified signal voltage secured when a signal at the input to section 34 is tuned within the band uniformly passed by the intermediate-frequency selectors of section 34. The

sharp peak of curve 118 is caused by the action of the trap circuit in relaxing the A. V. C. voltage, hence increasing the amplification in section 34, when the carrier frequency is tuned to the trap frequency, 175 kilocycles. The resulting signal level at the input of section 36 reaches a sharp maximum as shown by curve 118 when the carrier is tuned to 175 kilocycles. The effect of the trap characteristic 118, in enabling the receiver to be properly tuned, will be fully brought out in the following discussion of the quieting system.

Automatic quieting

The automatic quieting action is the means for quieting the receiver at all times except when the receiver is properly tuned at either edge of the intermediate-frequency band. This system quiets undesired noises and distorted signals which would otherwise be reproduced when the receiver is not properly tuned to a useful signal. The quieting system cooperates with the trap 41 and the automatic volume control system to produce the "selective admission".

The quieting action is obtained by reason of the peculiar transmission, or transfer ratio, characteristic which is imparted to the pentode translating tube 55. To produce the single sideband type of reception, the switches 19 and 80, ganged for unitary operation, are thrown to the right so that switch 80 connects a resistor 81 in series between the screen 202 and the positive terminal of the direct voltage source 203. Resistor 81 has a relatively low value so that the voltage at screen 202 is substantially independent of screen current. A relatively high resistor 78 is connected in series between the anode 177 and the positive side of direct voltage source 205, the latter source being in series with source 203.

The relationship between the grid bias and the anode current of this pentode as thus connected is shown by curve 116 of Fig. 6b, wherein grid bias voltage is plotted against plate current in milliamperes. The anode voltage is reduced nearly to zero by an anode current flow of about 1 millampere through resistor 78, the remaining space current of the tube flowing to the screen 202. It is observed from curve 116 that when the negative grid bias reduces to about 9 volts, the plate current rises to about 1 millampere. Hence, for values of negative grid bias less than 9 volts, the plate voltage is substantially zero. For values of negative grid bias greater than 9 volts, the total space current is reduced and therefore the anode current falls rapidly, approaching zero beyond 15 volts bias.

The gain, or amplification, ratio of quieting tube 55 depends on the slope of curve 116 and is, therefore, a maximum in the region between the limiting values of 10 and 12 volts negative bias. The slope in this region represents an amplification of about fifty times, for the particular tube arrangement used. The relative amplification, or repeating ratio, of the pentode bias controlled repeater tube 55 is represented by curve 117 of Fig. 6c, in which percentage amplification is plotted against negative grid bias. For the particular tube arrangement described, 11 volts is seen to be a critical value of grid bias, since only those bias voltages which are at and near this value permit the tube to translate the signals.

In operation, the intermediate-frequency voltage at the secondary of coupling system 162 is rectified linearly in diode 55', and the rectified voltage appears across resistor 83 and condenser 75

82. Condenser 82 is so small as to have a negligible effect at audio frequencies and serves with resistor 84 and condenser 85 to remove the carrier-frequency components from the rectified voltage. The lower audio-frequency modulation components of the rectified voltage follow the path of elements 86, 87 and 88 to the control grid 176 of pentode 55. The impedance of the input circuit of tube 55 to higher audio frequencies is decreased by condenser 89 and a relatively low resistor 90, connected across the high resistor 87. This lower impedance path 89, 90 compensates for the selection of the lower audio frequencies of both sidebands. Grid bias voltage proportional to the average rectified signal voltage is applied to control grid 176 through a path including the high resistors 84, 91 and 92. Condenser 93 has a sufficiently large capacity to bypass all modulation components at this biasing connection.

The entire direct voltage appearing across resistor 83 is applied to grid 176 as a quieting bias. But only a small portion (about $\frac{1}{6}$) of the audio-frequency component of rectified voltage is applied to grid 176 as a signal. This limits the grid swing to a value which will not cause the peaks of the waves to lie beyond the straight portion of curve 116, thereby avoiding distortion.

The bias voltage derived from diode 55' varies in accordance with curve 118 of Fig. 6a. It is observed from curve 118 that the trap 41 which produces this characteristic is so proportioned as to cause the critical bias voltage (11 volts in Fig. 6b) to be obtained when the carrier is tuned to either edge of the selected intermediate-frequency band (1.5 kilocycles on either side of the center in this case). Because of this relationship between curves 116 and 118, pentode tube 55 is operative to pass signals only when the intermediate-carrier frequency is properly tuned for single sideband reception at either edge of the selected band.

Visual tuning indicator

45 There is connected in series with a resistor 78 in the anode circuit of tube 55 a visual tuning indicator in the form of a milliammeter 90. When the receiver is in operation, this milliammeter has a maximum deflection of 1 millampere and a minimum deflection of zero, as can be observed from Fig. 6b. The milliammeter indicates the proper tuning position for single sideband operation when the meter reads half deflection at 0.5 millampere. Fig. 6b shows this to be the anode current which flows when the critical grid bias voltage of 11 volts is reached. Curve 118 of Fig. 6d and curve 120 of Fig. 6e show, respectively, the variations in anode current and in relative amplification in tube 55 when the intermediate-carrier frequency is tuned in the region of 175 kilocycles. The two sharp peaks of curve 120 show the audibility points of correct tuning of the intermediate-carrier frequency at 1.5 kilocycles above or below the mid-point frequency of 175 kilocycles, and correspond to mid-scale deflection of the tuning meter.

Double sideband reception

To cause the receiver to operate as a double sideband receiver, switches 79 and 80 are thrown to the left position. Switch 80 then causes resistor 81 to become open-circuited so that the screen voltage is furnished from the positive side of voltage source 205 through a relatively high resistor 86. Switch 80 also then closes a con-

nection, placing in the grid bias circuit a resistor 97 which reduces the bias voltage to a lower value than that used for the single sideband adjustment. A bias voltage which produces a 0.5 milliampere anode current when a signal is tuned to 175 kilocycles has been found correct. The average screen voltage and screen current are, under this condition, held nearly constant for small values of grid bias. This results in an amplifier plate current-grid bias curve of normal shape, in which the slope is always positive.

The switch 79, in the left position, now short-circuits resistor 95 which reduces the audio-frequency voltage applied to the control grid 176. At the same time, this provides a lower impedance path to ground for the higher audio frequencies through resistor 94. The increased amplification of the high audio frequencies (under single sideband reception) is thus removed, since high audio-frequency compensation is not required under double sideband reception. Resistors 94 and 95 are proportioned to cause the audio-frequency voltage at the anode 177 to be the same for both single and double sideband reception.

Under this condition of double sideband reception, the receiver is tuned to a minimum deflection on the tuning meter which will be at about mid-scale. This corresponds to tuning so that the intermediate-carrier frequency is exactly at the center of the intermediate-frequency selected band (175 kilocycles) and is indicated by the loudest signal.

In the single sideband condition of operation, all signals of intensity greater than a threshold value are received at two points on the tuning dial corresponding to one or the other of the two sidebands. Signals of greater or lower intensity than the threshold value can be received by throwing switches 79 and 80 to the double sideband position. The signal is then received at only one point corresponding to center-tuning and highly selective double sideband reception. The higher audio-frequency response, and consequently the noise which attends signals of low intensity, are thus reduced by this highly selective double sideband reception.

It is a feature of the present invention that with switches 79, 80 in the position for single sideband reception, signals of lower than threshold intensity are received automatically at only one point corresponding to center tuning and double sideband reception.

The transition from the single sideband to the double sideband operation takes place automatically when the signal intensity drops only a certain amount below the threshold value. The reason for this transition can be observed from an inspection of curve 108 of Fig. 6a. This curve represents rectified voltage applied as a bias to the grid of the quieting tube when the signal tuned in is just strong enough so that the peak reaches the critical value of 11 volts. Under this condition, the signal is tuned in at the point on the dial corresponding to 175 kilocycles.

Oscillator-modulator

The oscillator-modulator tube 52 is a hexode having in the order named the following electrodes: cathode 207; inner grid 208; inner screen, 70 or oscillator-anode, 209; outer grid 210; outer screen 211; and anode 212. This type of tube and its associated oscillator-modulator circuits are disclosed in my U. S. Letters Patent 1,958,027, issued May 8, 1934.

Briefly, the oscillatory system is associated with the inner electrodes 207, 208 and 209. A feedback coil 213 is connected in series with a choke coil 217 and a direct voltage source 218, between the inner screen, or oscillator anode 209 and ground. Coil 213 is coupled to a coil 214 included in the oscillatory system. The oscillator frequency-determining circuit 99 is composed of coil 214, a variable condenser 215 and a fixed (though adjustable) condenser 216. A coupling condenser 219 is connected from the junction of elements 213 and 217 to the junction of elements 214 and 216. Hence, there is capacitive as well as magnetic feedback coupling from electrode 209 to the oscillator circuit 99. This arrangement of the oscillatory system provides a uniform oscillator voltage over the entire frequency range of the oscillator.

The oscillatory circuit 99 is also coupled both capacitively and magnetically to the circuit of grid 208. The magnetic coupling exists between coil 214 and a coil 220 of the grid-cathode circuit; and the capacitive coupling is due to a dead-end turn 221 connected with coil 220 and electrostatically associated with coil 214. By reason of this arrangement, any capacity change in the circuit of grid 209 produces a frequency change which is very small and substantially the same for all oscillator frequencies.

The coupling elements 213, 219, 220 and 221, when adjusted to the proper values, remain permanently fixed at such desired values.

Volume level control and tone compensation

The volume level control and tone compensator comprises the adjustable voltage divider 100 at the input of audio amplifier tube 56. The voltage divider is designed to provide an approximately exponential relationship between the decibels attenuation and angle of rotation of the contact control knob (represented by the arrow).

Experience teaches that the normal ear desires less change of intensity at the higher and lower audio-frequencies than at the medium audio frequencies. The volume level control is designed to satisfy this desire of the ear. At the greatest volume, the contact of potentiometer 100 is located at the upper end thereof. In this position, the elements associated with the potentiometer are proportioned so that the fidelity is in accordance with curve 121 in Fig. 5, this figure being a graph in which relative gain in decibels is plotted against frequencies of the selected audio range.

At very low volume level, the contact is at the lower end of potentiometer 100, condensers 104 and 105 and resistors 103 and 106, causing the fidelity characteristic to slope upward toward the lower frequencies, as shown by curve 122. Condensers 101 and 102 cause curve 122 to slope upward toward the higher frequencies. At mean volume level, the fidelity curve is substantially flat as shown by curve 109. In this potentiometer arrangement, elements 101 and 102 are small equal condensers which reduce the attenuation changes at the higher audio frequencies; and elements 104 and 105 are large equal condensers which reduce the attenuation changes at the lower audio frequencies.

It should be understood that the foregoing description applies to a preferred embodiment of the invention and should not be construed as a limitation thereof. For example, values other than those used herein, of voltage, grid bias, frequency and band width, may be employed. Like-

wise, vacuum tubes of equivalent performance but having more or less electrodes per tube may be substituted. Although, in the drawings, the direct voltage sources are, for convenience, shown symbolically in the form of separate batteries, it should be understood that a common source of power supply of any of the conventional types may be used rather than separate sources in the several locations where batteries are represented.

What is claimed is:

1. In a modulated-carrier-signal receiver, a rectifier circuit for rectifying the signal to produce a modulated unidirectional voltage, a bias-controlled modulation voltage repeater stage having input and output circuits, means for applying at least a part of said unidirectional voltage to said input circuit as bias and input modulation voltage, and means for causing the transfer ratio of said stage to be maximum for a predetermined value of bias voltage and to approach closely zero for all substantially different values, whereby the output modulation voltage is caused to be substantial only when the signal causes said bias voltage to be substantially equal to said predetermined value.

2. In a modulated-carrier-signal receiver, a rectifier circuit for rectifying the signal to produce a modulated unidirectional voltage, a modulation-voltage repeater stage including a pentode repeater having a cathode, control grid, screen, suppressor and anode situated in the order named, means for impressing said unidirectional voltage on said grid as the modulation-voltage input and as a bias voltage negative relative to said cathode, means for impressing on said screen a substantially constant direct voltage positive relative to said cathode, means for maintaining said suppressor at substantially zero voltage relative to said cathode, means for impressing on said anode a direct voltage from a source positive relative to said cathode, and a resistor between said anode and said source for reducing the anode direct voltage to approximately half the source voltage for a substantial negative value of said bias voltage, whereby the modulation-voltage output of said repeater stage is caused to be sharply maximum for the value of modulation-voltage input corresponding to said value of bias voltage.

3. In a modulated-carrier-signal receiver, a rectifier circuit for rectifying the signal to produce a modulated unidirectional voltage, a modulation-voltage repeater stage including a pentode repeater having a cathode, control grid, screen, suppressor and anode situated in the order named, means for impressing said unidirectional voltage on said grid as the modulation-voltage input and as a bias voltage negative relative to said cathode, means for impressing on said screen a substantially constant direct voltage positive relative to said cathode, means for maintaining said suppressor at substantially zero voltage relative to said cathode, means for impressing on said anode a direct voltage from a source positive relative to said cathode, and a resistor between said anode and said source for reducing the anode direct voltage to a value not exceeding half the source voltage for a substantial negative value of said bias voltage, whereby the amplification in said repeater is caused to increase substantially with increasing input amplitude for input amplitudes corresponding to voltages less than said substantial value.

4. In a modulated-carrier-signal receiver including a carrier-frequency amplifier, a rectifier,

- and a modulation-frequency amplifier having cathode, control grid, screen and anode, means for automatically regulating the output voltage of said carrier-frequency amplifier, means for coupling said output voltage to said rectifier for rectification, means for coupling to the grid-cathode section of said modulation-frequency amplifier the resulting modulated unidirectional voltage, means for impressing on said screen a substantially constant direct voltage positive relative to cathode, and means for impressing on said anode through a high resistor a direct voltage positive relative to cathode, said resistor and both said direct voltages being proportioned to cause the modulation-frequency amplification to be sharply maximum at a predetermined value of grid-bias voltage substantially negative relative to cathode, whereby a predetermined value of carrier-frequency output voltage is caused to produce said grid-bias voltage and thereby to produce maximum modulation-frequency voltage across said resistor.
5. In a modulated-carrier-signal receiver, a carrier-frequency amplifier including a band selector, a control circuit including a control rectifier and a trap circuit sharply tuned to the center frequency of said band for coupling the output of said amplifier to said control rectifier, means for reducing the amplification in said amplifier with increasing rectified voltage from said control rectifier, a main rectifier for rectifying the output of said amplifier to produce a modulated unidirectional voltage, a modulation-frequency amplifier for amplifying the modulation-frequency component of said unidirectional voltage, means for impressing on said modulation-frequency amplifier a bias voltage which varies in accordance with said unidirectional voltage, said modulation-frequency amplifier having an amplification ratio which decreases abruptly as said bias voltage departs either way from a predetermined value, said control circuit being proportioned to provide a rectified voltage of an amplitude which maintains the carrier output 45 of said amplifier at a value which causes said bias voltage to assume said predetermined value when the carrier frequency equals either of the two frequencies differing from said center frequency by a predetermined difference not exceeding half the band width of said band selector, and at a substantially greater value when the carrier frequency equals said center frequency.
6. In a modulated-carrier-signal receiver, a band selector, a carrier-frequency amplifier, means for causing the output of said receiver to be maximum only at a predetermined critical value of amplified carrier voltage, and auxiliary means for automatically maintaining the amplitude of said amplified carrier voltage nearly independent of the received signal intensity, said auxiliary means including a sharply selective circuit tuned to the center frequency of said band for causing said amplified carrier voltage to exceed substantially said critical value only when the carrier is tuned substantially to said center frequency, and said auxiliary means being proportioned to maintain said amplified carrier voltage at said critical value, and thereby to cause the output of said receiver to be maximum, only when the carrier frequency equals either of the two frequencies differing from said center frequency by a predetermined difference not exceeding half the band width of said band selector.
7. In a modulated-carrier-signal receiver according to claim 6, adjustable means for enabling

said sharply selective circuit to be tuned to said center frequency in the band of said selector, whereby the two frequencies of maximum output may be adjusted relative to said center frequency without altering the difference between said two frequencies, which differ from said center frequency by a predetermined difference not exceeding half the band width of said band selector. 5

8. In a modulated-carrier-signal receiver, a band selector for selecting a frequency band equal in width to one of the modulation sidebands of a modulated-carrier signal, tunable means for adjusting the carrier to any frequency within said band, means for greatly attenuating the output of said system except when the carrier is adjusted to either edge of said band, and a switch for disabling said output-attenuating means to permit the operation of said system when the carrier is adjusted to the center of said band. 15

9. In a modulated-carrier-signal receiver, a band selector for selecting a frequency band equal in width to one of the modulation sidebands of a modulated-carrier signal, tunable means for adjusting the carrier frequency to any frequency within said band, selective automatic control means for causing input signals of an intensity greater than a predetermined threshold value to produce maximum output when the carrier frequency is adjusted to either of the edges of said band, said control means being proportioned 30 automatically to cause signals of an intensity less than said threshold value to produce maximum output when the carrier frequency is adjusted to the center of said band.

10. In a modulated-carrier-signal receiver, a band selector for selecting a frequency band equal in width to one of the modulation sidebands of a modulated-carrier-signal, tunable means for adjusting the carrier frequency to any frequency within said band, selective automatic control 40 means for causing signals of an intensity greater than a predetermined threshold value to produce maximum output from said receiver when the carrier frequency is adjusted to either edge of said band, said control means comprising auxiliary 45 means for maintaining the output voltage of said band selector substantially independent of the intensity of said signals above said threshold value, a rectifier producing a unidirectional voltage dependent on said output voltage, means for impressing the modulation components of said unidirectional voltage on the control grid of an amplifier tube adjusted to amplify only at or near a critical value of grid bias, a connection from said rectifier to said grid for controlling said 55 grid according to the average value of said unidirectional voltage, a trap circuit associated with said auxiliary means for causing said output voltage to reach a sharp maximum when said carrier frequency is adjusted to the center of 60 said band, whereby said critical value of grid bias is substantially exceeded when said carrier frequency is so adjusted, and said critical value is obtained only when the carrier frequency is adjusted to either of the edges of said band. 65

11. In a modulated-carrier-signal receiver for receiving either one of the modulation sidebands of a modulated-carrier signal, a band selector for selecting a frequency band equal in width to one of said sidebands, tunable means for adjusting the carrier frequency to any frequency within said band, a tuning meter for indicating the space current of a vacuum tube in said system, means for limiting said space current to a maximum meter deflection in the absence of a 75

- 5 signal, selective automatic control means for reducing said space current to half maximum deflection when said carrier frequency is adjusted to either of the edges of said band, and to a very small deflection when said carrier frequency is adjusted to the center of said band.
- 10 12. In a wave signaling system designed to transmit a band of frequencies comprising a carrier frequency and at least one modulation side-band, a signal-translating stage comprising means for producing a unidirectional voltage which varies with variations in frequency, within said band, of signal input to said stage, a bias-controlled repeater having a repeating ratio which decreases abruptly as the bias departs either way from a predetermined value, and means for applying said unidirectional voltage to said repeater as a bias voltage whereby the amplitude of the signal output from said repeater is caused to be sharply maximum for a critical value of frequency, within said band, of signal input.
- 15 13. In a wave signaling system designed to transmit a band of frequencies comprising a carrier frequency and at least one modulation side-band, a signal-translating stage comprising means for producing a unidirectional voltage, a selective circuit excited from the signal input of said stage and effective to vary the unidirectional voltage between predetermined minimum and maximum values in accordance with variations in frequency, within said band, of signal input to said means, a bias controlled repeater having a repeating ratio which decreases abruptly as the bias departs either way from a predetermined value, and means for applying said unidirectional voltage to said repeater as a bias voltage, whereby the amplitude of the signal output from said repeater is caused to be sharply maximum for a critical value of frequency, within said band, of the signal input.
- 20 14. In a wave signaling system designed to transmit a band of frequencies comprising a carrier frequency and at least one modulation side-band, a signal-translating stage comprising a rectifier for producing a unidirectional voltage proportional to the input carrier amplitude of said stage, a selective circuit for varying the carrier amplitude of the input to said stage between predetermined minimum and maximum values with variations in frequency, within said band, of signal input to said stage, a bias-controlled repeater having a repeating ratio which decreases abruptly as the bias departs either way from a predetermined value, and means for applying said unidirectional voltage to said repeater as a bias voltage, whereby the amplitude of the signal output from said repeater is caused to be sharply maximum for a critical value of frequency within said band of the signal input to said stage.
- 25 15. In a wave signaling system designed to transmit a band of frequencies comprising a carrier frequency and at least one modulation sideband, a signal-translating stage, control means for automatically maintaining the carrier amplitude of the input to said stage within a relatively narrow range for a wide range of input carrier amplitudes to said system, said stage comprising a rectifier for producing a unidirectional voltage proportional to the input carrier amplitude of said stage, a selective circuit for modifying the action of said control means to vary the carrier amplitude of the input to said stage between predetermined minimum and maximum values with variations in frequency, within said band, of signal input to said stage, a bias-controlled repeater having a repeating ratio which decreases abruptly as the bias departs either way from a predetermined value, and means for applying said unidirectional voltage to said repeater as a bias voltage, whereby the amplitude of the signal output from said repeater is caused to be sharply maximum for a critical value of frequency within said band of the signal input to said stage.
- 30 16. In a modulated-carrier-signal receiver, a selective network for selecting a band of frequencies including the carrier and at least one of the side-bands of modulation, a tunable frequency changer for changing the carrier frequency of the signal to any frequency within said band, control means for automatically maintaining the carrier amplitude of the output of said network substantially independent of the carrier amplitude of the input thereto for a wide range of input carrier amplitudes on carrier frequencies within said band, a rectifier coupled to the output of said network for producing a unidirectional voltage proportional to the carrier amplitude thereof, a selective circuit for causing the output carrier amplitude and therefore said unidirectional voltage to vary between predetermined minimum and maximum values as the frequency changer is tuned to change signal carrier frequency to different frequencies within said band, and a bias-controlled signal repeater coupled to the output of said network and having applied thereto said unidirectional voltage as a bias voltage, the circuit of said repeater being proportioned to secure maximum repeating ratio for an intermediate value of said unidirectional voltage and greatly reduced repeating ratio for said minimum and maximum values of said unidirectional voltage, whereby the output of said repeater is caused to be substantial only for the adjustment of the tuning to secure an intermediate value of carrier amplitude of the output of said network.
